UNITED STATES PATENT OFFICE.

JOHN ROBERT THOMPSON, OF AMERICUS, GEORGIA.

SEAL-LOCK.

SPECIFICATION forming part of Letters Patent No. 700,258, dated May 20, 1902.

Application filed April 13, 1901. Serial No. 55,743. (No model.)

To all whom it may concern:

Be it known that I, JOHN ROBERT THOMPSON, a citizen of the United States, residing at Americus, in the county of Sumter and State 5 of Georgia, have invented a new and useful Seal-Lock for Car-Doors, of which the following is a specification.

The invention relates to improvements in seal-locks for car-doors.

10 The object of the present invention is to improve the construction of car-door locks and to provide a simple and comparatively inexpensive one capable of being readily operated and adapted to be effectively sealed 15 when closed, so as to plainly indicate when it has been opened.

With these and other objects in view the present invention consists in the combination and arrangement of parts, as will be herein- 20 after more fully described, shown in the accompanying drawings, and particularly pointed out in the appended claims, it being understood that changes in the form, proportion, size, and minor details may be made 25 within the scope of the claims without departing from the spirit or sacrificing any of the advantages of the invention.

In the drawings, Figure 1 is an inside elevation of a portion of a car, showing the im- 30 proved door mounted therein, parts being broken away to show the connection between the door and the tracks therefor and also to show the locked connection between the door and the car-frame. Fig. 2 is a vertical sec- 35 tional view thereof. Fig. 3 is a detail en- larged sectional view taken on the line 3-3 of Fig. 1. Fig. 4 is a similar view showing the door in the act of closing. Fig. 5 is a detail enlarged sectional view taken through the bot- 40 tom of the door and the car with the former in its closed position. Fig. 6 is an enlarged detail sectional view taken through the top of the car and door. Fig. 7 is a detail sec- 45 tional elevation showing the means for lock- ing the lock-operating handle. Fig. 8 is an enlarged detail sectional view taken longitudinally through the outer end portion of the handle to show the sealing apparatus. Fig. 9 is a similar view at right angles to Fig. 50 8. Fig. 10 is a view similar to Fig. 9 with the device in its locked position. Fig. 11 is a

transverse sectional view on the line $\alpha\alpha$ of Fig. 9. Fig. 12 is a similar view on the line zz of Fig. 10. Figs. 13 and 14 are detail views of the frangible seal. Fig. 15 is a detail plan 55 view of the stationary plug in the handle. Fig. 16 is a detail plan view of the plug and the locking-bolt, showing the position of the seal in the locked position of the bolt.

Like characters of reference designate cor- 60 responding parts in all of the figures of the drawings.

Referring at first more particularly to Figs. 1 to 6, inclusive, 1 designates the side of a car, and 2 an ordinary slidable car-door, which 65 in the present invention is provided with a beveled marginal edge to fit snugly the correspondingly-beveled marginal edge of the doorway in order that the door may lie flush with the outer side of the car when closed. 70

For the support of the door when the latter is open and drawn laterally out of the doorway there is provided a bottom track 3 in the form of a round rod, which is located below the lower edge of the door and is sup- 75 ported outwardly from the car by means of a plurality of brackets, one of which has been shown at 4. Each bracket is secured to the bottom sill or side of the car and engages the track from the rear side only, so that the top 80 and inner side thereof may be free from ob- structions. In the bottom edge of the door there is provided a longitudinal slot or opening 5 for the reception of a fixed rod 6, and in the outer side of the door there is provided 85 a pair or more of vertical slots or openings, one of which has been illustrated at 7 to ex- pose the rod. Upon this rod are hinged the hangers 8, which are introduced through the respective slots or openings 7 and project 90 downwardly through the longitudinal slot 5, that opens outwardly through the bottom of the door, or only the opening 7 may open through the bottom of the door, as may be desired. This hanger is preferably formed 95 in two opposite members, which have their upper ends provided with a detachable hinged or pivotal connection, so as to embrace the rod loosely and form a hinged connection therewith to permit of an outward swing of 100 the hanger upon the rod as a center. The lower ends of the hanger members are spread,

so as to form a fork for the reception of a grooved roller or wheel 9 to travel upon the track 3. By this arrangement the hanger assumes an inwardly-inclined position, as shown 5 in Fig. 5, when the door is closed into the doorway, and when the door is pulled laterally outward, so as to slide upon the track, the hanger swings outwardly upon the track as a center until it assumes a vertical position. (Shown in Fig. 2.)

To lock the door when closed, there are provided the top and bottom pairs of lock-bars 10, the members of each pair having their inner ends connected to the inner side of the door by means of a common pivotal connection 11, from which they extend laterally outward in opposite directions across the inner side of the door. The outer end of each member is provided with a locking-bolt 12, 15 which has its inner end pivotally connected to the adjacent bar, as at 13, and works freely through a slot or opening 14, formed transversely through the adjacent side edge of the door, and is designed to be shot outwardly, 20 so as to take into a socket 15, formed in the adjacent edge of the doorway in the car, whereby the door is locked. The locking-bolts at one or rather each edge of the door carry a vertical plate or metal strip 16, which 25 is connected to both top and bottom bolts, so as to move therewith, and normally lies within a vertical slot in the edge of the door, so as to be carried outwardly with the bolts and into a corresponding slot or groove 17, formed 30 in the edge of the doorway, as illustrated in Figs. 3 and 4, the strip being partly in the door and partly in the car when the door is closed, whereby the joint is effectually closed and rendered weather-proof and fireproof. 35

As shown in Fig. 4, the outer end of the locking-bolt is beveled at substantially right angles to the bevel of the door edge and doorway, so that when the bolt is shot outwardly and the door is moving laterally inward the beveled end of the bolt will strike the outer edge of the socket 15 in the edge of the doorway, and thereby aid in drawing the door into the doorway.

The lock-bars are simultaneously operated 40 by means of a tumbler 18, pivotally mounted at about the center of the inner side of the door and to which are pivotally connected the links 19, which have their outer ends pivotally connected, as at 20, to the intermediate portions of the respective lock-bars 10, there being a link for each bar. When the tumbler is rotated in one direction, the links 19 are moved outward, and they carry with them the adjacent ends of the bars 10, thereby swing- 45

ing the said bars out of alignment and arranging them in a position at an angle to each other, whereby the bolts 12 are withdrawn from engagement with the sockets or keepers in the edge of the doorway. The door is then 50 adapted to be moved outward, so as to be supported upon the lower track.

For the convenient manipulation of the lock-bars from the exterior of the car there is provided a rotatable shaft or spindle 18', (shown in Figs. 2 and 7,) said spindle being 55 fixed to the center of the tumbler and passing rotatably through the door, the outer end of the spindle being mounted in a central opening in a combined stop and lock-plate 19', fixed to the outer side of the door. In 60 the center of the outer face of this plate and surrounding the projected end of the spindle there is provided a circular recess 20', and in the marginal wall of this recess there are provided a pair of notches or sockets 21, which 65 are disposed at substantially right angles to each other, the outer face of the plate also being cut away or reduced to form a quadrant-shaped recess, the opposite walls of which form stop-shoulders 22, corresponding 70 to the notches or sockets 21. A tubular crank-handle 23 has its inner end slightly flattened and provided with a polygonal opening 24 for the snug reception of the polygonal projecting end of the spindle 18', said handle lying 75 within the quadrant-shaped recess and projecting a suitable distance beyond the peripheral edge of the plate and limited in its movement by the opposite stop-shoulders 22. Within the handle is an endwise-movable handle-locking bolt or rod 25, which is designed to be shot outwardly through a diametric opening 26 in the outer polygonal end of the spindle and into one of the sockets 21 for the purpose of locking the handle against movement when lying against the respective stop-shoulders 22 and at its opposite limits. It 80 will thus be understood that by swinging the handle from one limit to the other the spindle and tumbler will be rotated and the lock-bars operated through the medium of the links.

It is designed to automatically force the door laterally outward by the withdrawing of the locking-bolts, and to accomplish this 85 feature there is provided a pair or more of vertical shifting arms or members 26', (best shown in Figs. 1 and 6,) having their lower ends pivotally connected to the intermediate portions of the respective upper lock-bars 115 and working loosely through vertical slots or openings 27, formed through the top edge of the door. At the inner upper edge of the respective shifting-arms there is mounted an antifriction-roller 28, which projects slightly 120 above the top edge of the arm, and adjacent to the outer side of the arm there is provided a longitudinal bifurcation or slot 29 in the upper end of the arm, thereby forming a fork to slidably embrace the lower edge of a flat 125 upper track 30, hung from the upper portion of the outer side of the car by means of suitable brackets 31. By this arrangement the upper end of the door is guided upon the upper track when the door has been drawn outwardly. When the locking-bolts are shot 130 outwardly to lock the door and the latter is

within the doorway, the shifting-arms are drawn downwardly by the movements of the upper locking-bars, and when the locking-bars are raised by the unlocking of the door 5 the shifting-arms will be thrust simultaneously upward, whereby the antifriction-rollers strike the upwardly and outwardly inclined upper edge of the doorway, and thus automatically force the door laterally outward 10 until the lower edge of the upper track is embraced by the fork portions of the shifting-arms, the lower hinged hangers 8 accommodating themselves to the lateral movement of the door. When the door has thus been 15 moved out of the doorway, it is free to be slid endwise upon the tracks to uncover the doorway in the car. To close the door, the handle 23 is swung to its opposite limit, thereby drawing the guiding and shifting arms 20 downwardly below the upper edge of the door to permit of the latter being pushed laterally into the doorway and the locking-bolts being shot into the keepers or sockets on the car. It will be understood that the 25 movements of the shifting-arms and the locking-bolts are so proportioned that the arms will be disengaged from the tracks before the bolts project beyond the door edge in order that the door may enter the doorway 30 before the bolts are projected.

The handle is provided with a sealing mechanism housed within it and adapted to prevent the locking device from being operated without breaking the seal. The locking bolt 35 or bar 25, which is reduced at its inner portion, as illustrated in Fig. 7, is provided with an outer portion slidably mounted within the handle. The outer portion of the bolt is made semicylindrical, as at 32, and this reduction provides a shoulder 33 at the inner end of the semicylindrical portion. This semicylindrical portion is recessed at the inner face to provide a semitubular portion 34. The semitubular portion forms a shoulder 35 at the center of the semicylindrical outer portion of the bolt, and the shoulder is provided with a beveled notch 36 of less width than the groove or recess of the semitubular portion. The side edges of the semitubular portion 40 are provided with recesses 37, extending from the shoulder 35 to the outer end of the bolt.

In the space provided by the semicylindrical portion of the bolt is fitted a fixed semicylindrical block or plug 38, and the shoulder 33 of the bolt lies against the inner end of the plug to limit the outward movement of the locking-bolt when the latter is in its unlocked position. The semicylindrical block 45 or plug is provided at the outer portion of its inner face with a recess 39 of substantially the same width as the beveled notch 36 and of approximately the length of the longitudinal recesses 37, of the semitubular portion of the locking bar or bolt. Within the recess 39 is pivoted a swinging latch 40, secured at its outer end 41 to the block or plug and hav-

ing its inner end free and yieldingly supported by a spring 42, interposed between the latch and the plug or block and seated in a 70 socket of the latter. The free end of the latch lies against the back wall of the notch 36 to prevent it from entirely closing the upper longitudinal recess 37 in the semitubular portion of the locking-bolt. The inner portion 75 of the block or plug is provided with a lateral opening 43, which registers with an opening 44 in the handle, and the latter is also provided at its top with a slot or opening 45, which is adapted to register with the 80 adjacent longitudinal recess of the locking-bar to permit a frangible seal 46 to be introduced into the device, and the said seal is received within a seal-chamber formed by the semitubular portion of the locking-bar, whereby 85 the seal is carried by the bar when the latter is reciprocated. When the locking-bar is moved forward to its engaging position, the frangible seal 46 is carried to a position opposite the aligned or registering openings 43 90 and 44 of the plug and the handle and is exposed through the said openings. The seal 46 is locked in this position by the spring-actuated latch 40, which snaps back of the rear end of the seal and into engagement 95 therewith at the outer end thereof, thereby locking the bolt in the position illustrated in Fig. 10 of the drawings. The bolt cannot be withdrawn from this position without breaking the seal, which operation is effected by 100 inserting a stick or any suitable implement through the aligned openings 43 and 44. The broken parts of the seal will be received within the semitubular seal-chamber and will be discharged therefrom through the outer 105 open end of the handle when the latter is swung downward to a substantially vertical position.

To facilitate endwise movement of the locking-bolt in the handle, there is provided 110 a rotatable sleeve 47, mounted upon the outer portion of the handle at the openings thereof and fitting against an annular stop shoulder or collar 48 of the said handle to prevent it from moving inward on the same. The lower 115 side of the sleeve is provided with an internal spiral groove or slot 49, receiving a stud or projection 50 of the locking-bolt. The stud or projection 50 is located between the ends of the locking-bolt, which is reciprocated 120 when the sleeve is partially rotated. The handle is provided with a longitudinal slot 51, through which passes the stud or projection 50 of the locking-bolt.

The frangible seal, which is preferably rectangular, as illustrated in Fig. 13 of the drawings, may be constructed of any suitable material, and the inner or rear face, which is unexposed, is provided with a plurality of longitudinal grooves 52. These grooves, which 130 are V-shaped in cross-section, weaken the seal and enable it to be readily broken by pressure thereon when an instrument is introduced through the registering openings 43 and

44. The sleeve is also provided with an opening 53, which registers with the said openings 43 and 44 when the bolt is in its engaging position. A slot or opening 54 is formed in the 5 sleeve and is adapted to align with the opening 45 of the handle and the longitudinal recesses 37 when the bolt is retracted, whereby the seal may be readily introduced into the seal-chamber. The beveled back wall of the 10 notch 36 is adapted to force the latch 40 into the latch-recess when the locking-bolt is drawn outward, and by this construction the lock is prevented from binding or interfering with the quick withdrawal of the bolt.

15. From the foregoing description it is apparent that the handle for manipulating the lock is designed to be swung in the path of a quarter-circle to lock and unlock the locking-bolts and has a handle-locking bolt which is arranged to engage with a fixed member on the car-door to lock the handle against accidental movement at its opposite limits. Moreover, there is provided a rotatable sleeve for manipulating the handle-locking bolt, which is designed to be rotated in one direction to withdraw the bolt and permit of the insertion of a seal and also to permit of the handle being swung to its opposite limit, the opposite rotation of the sleeve being designed to force the 25 bolt into locked engagement with the fixed keeper therefor and to move the seal into position for locking the bolt against accidental withdrawal and to an exposed position for breakage whenever desired to withdraw the 30 bolt.

35. In order that there may be a positive interlock between the seal and the stationary plug in the locked position of the bolt in addition to that formed by the spring-catch 40, the inner side of the plug 38 is provided with a marginal notch 54, extending around the opening 43 therein and for the reception of the seal in the locked position of the bolt 25, as indicated in Fig. 16 of the drawings. When the 40 seal is opposite the opening in the plug, it is moved laterally, so as to lie partly in the notch in the bolt and partly in the notch of the plug, by means of a spring 55, carried within the semitubular portion of the bolt. As indicated 45 in Fig. 15, it will be seen that the spring-latch 40 is narrower than the seal, so as to engage the intermediate portion of the rear edge thereof, while the opposite ends of said edges lie against the opposite shoulders 56, formed 50 on the plug by the notch 54, whereby should the spring-catch refuse to engage with the seal the latter will still form an interlocked connection between the bolt and the handle, and thus preclude the possibility of unlocking 55 the bolt without also breaking the seal.

60. What is claimed is—

1. A lock comprising a pair of oppositely-disposed swinging locking-bars pivoted at their inner adjacent ends to fixed supports, 65 the outer terminal locking-bolts pivotally connected to the outer ends of the bars and ex-

tending longitudinally thereof and arranged in alinement with the same when in their engaging position, and operating mechanism pivotally connected with the swinging bars at 70 points between the ends thereof, substantially as described.

2. A lock comprising a pair of oppositely-disposed locking-bars pivoted at their inner ends to fixed supports, the outer terminal locking-bolts pivotally connected to the outer ends of the bars and extending longitudinally thereof and arranged in alinement with the same when in their engaging position, a rotatable tumbler, links pivoted to the tumbler 75 and similarly connected to the locking-bars at points between the ends thereof, substantially as described.

3. A lock comprising the upper and lower horizontally-disposed locking-bars provided 85 with inner terminal pivotal supports, the horizontally-disposed outer terminal locking-bolts pivoted to and extending longitudinally of the said bars and arranged in alinement with the same when in their engaging position, a central tumbler, links extending from the central tumbler to the locking-bars at 90 points between the ends of the latter, and the vertically-movable arms arranged above the upper locking-bars and pivoted to the same 95 at points between the ends thereof, substantially as described.

4. In a lock, the combination with a keeper, of a spindle, a handle fixed to the spindle and adapted to be oscillated to rotate the same, 100 and a reciprocating locking-bolt mounted on the handle and extending through and arranged to project beyond the spindle and adapted to engage the keeper, whereby the handle is locked, substantially as described. 105

5. A lock, having a rotatable spindle, a combined stop and bearing-plate having a central opening for the projection therethrough of the spindle, an enlarged recess formed in the outer side of the plate and about the spindle-opening, the marginal walls thereof being provided with a pair of spaced stop-sockets, opposite stop-projections upon the plate and corresponding with the notches, and a crank-handle fixedly connected to the projected end of 110 the spindle and movable in an arcuate path limited by the stop projections, and having an endwise-movable locking bar or bolt for engagement with the respective notches or sockets to lock the handle at opposite limits. 115

6. A lock, having a rotatable spindle, a combined stop and lock-plate, having a spindle-receiving opening, an enlarged recess formed around the opening and in the outer face of the plate, the walls of the recess having a pair 125 of spaced sockets or notches, the outer face of the plate also being provided with a quadrant-shaped recess intersecting the former recess, the opposite walls of the segmental recess forming stop-shoulders corresponding to 130 the notches or sockets, and a handle which is hollow and is fixedly connected to the outer

projected end of the spindle, said handle traveling in the segmental recess and limited by the opposite walls thereof, and also provided with an internal endwise-movable locking-bolt, that works through a diametric opening in the spindle and is adapted to take into the respective sockets to lock the handle at opposite limits.

7. In a lock, the combination with a keeper, 10 of an oscillatory handle provided with a tubular portion forming a casing and having a seal-inserting opening and a seal-exposing opening, a reciprocating bolt provided with a seal-carrying chamber, and a sleeve mounted 15 on the handle and connected with and adapted to reciprocate the bolt and provided with openings adapted to register with the openings of the casing, substantially as described.

8. In a lock, the combination with a keeper, 20 of an oscillatory handle, a reciprocating bolt mounted within the handle and carried by the same and adapted to engage the keeper, said bolt being provided with a seal-carrying chamber, and the said handle being provided 25 with seal-inserting and seal-exposing openings, and an automatically-operating locking device arranged to engage the seal when the bolt is in its engaging position, substantially as described.

30 9. A lock, having a slidable locking-bolt, a casing therefor, a frangible seal carried by the bolt, and a spring-actuated locking device mounted within the casing and constructed to snap automatically into locked engagement with the seal at the forward locked limit only of the bolt, the casing having a seal-inserting opening, and a seal-exposing opening located at the locked limit of the seal.

10. A lock, having a slidable locking-bolt, 40 a casing therefor, the outer end portion of the bolt which is within the casing being reduced, and provided in its inner side with a seal-receiving notch, a plug fitted fixedly within the casing and occupying the space 45 provided by the reduced portion of the bolt, the outer portion of the inner face of the plug having a recess corresponding to the notch in the bolt, a seal-engaging spring-actuated latch mounted within the recess, the inner 50 end portion of the plug having a lateral opening, and a frangible seal carried in the seal-receiving notch of the bolt and movable therewith to a position opposite the opening in the plug at the locked limit of the bolt, the latch being constructed to snap into engagement 55 with the outer end portion of the seal at the locked limit of the bolt, the casing having a seal-inserting opening alined with the seal-receiving notch of the bolt in the withdrawn 60 limit thereof, and a seal-exposing opening alined with the similar opening in the plug, to permit of access to the seal for breaking the same.

11. A lock, having a slidable locking-bolt, 65 a casing therefor, a frangible seal carried by the bolt and having an interlocked engage-

ment with the casing at the locked limit of the bolt, the casing having a seal-inserting opening and a seal-exposing opening at the opposite limits of the seal, and a rotatable adjusting-sleeve mounted upon the casing, and operatively connected to the bolt for sliding the latter in opposite directions.

12. A lock, having a slidable locking-bolt, a tubular casing therefor, having opposite 75 seal-inserting and seal-exposing openings, and a longitudinal slot, a frangible seal-carrier upon that part of the bolt within the casing and adjacent to the openings therein, and a rotatable sleeve mounted exteriorly upon 80 the casing, and having a spiral internal groove or slot, a projection upon the bolt and working in the slot of the casing and in the slot or groove of the sleeve, whereby a rotation of the latter will cause the bolt to move endwise, the sleeve having a seal-inserting opening corresponding to the similar opening in the casing at the withdrawn limit of the bolt, and a seal-exposing opening corresponding to the similar opening of the casing at the 90 locked limit of the bolt.

13. A lock, having a rotatable part, a tubular crank-handle connected thereto, and provided with an internal locking-bolt, a frangible seal carried by the bolt, and a locking device for engaging the seal when the bolt is in its engaging position, substantially as described.

14. A lock, having a rotatable part, a tubular crank-handle connected thereto, an internal slidable locking-bolt within the handle, a frangible seal carried by the bolt and within the handle, and engaging the same and the handle when the bolt is in its engaging position, a rotatable bolt-adjusting sleeve mounted externally upon the handle, and having an internal spiral groove or slot, and a projection upon the bolt and received within the groove or slot of the sleeve, the handle having a slot for the slidable reception of the 110 projection, and the sleeve and handle having corresponding seal-inserting openings which are alined at the withdrawn limit of the bolt, and corresponding seal-exposing openings which are alined at the locked limit of the 115 bolt.

15. A lock, comprising a casing, an endwise-slidable locking-bolt within the casing and having a seal-receiving seat in one side thereof, the inner side of the handle also having a 120 seal-receiving notch which is alined with the corresponding notch of the bolt in the locked position thereof, and means for moving the seal laterally from the bolt so as to lie partly in both notches and thereby form an interlocked connection between the bolt and the handle.

16. A lock, comprising a casing, having a seal-exposing opening, the inner side of which is provided with a marginal notch, an endwise-movable bolt within the casing, and having one side provided with a seal-receiving notch

that is alined with the notch and opening of the casing in the locked position of the bolt, and means for moving the seal laterally from the bolt and to lie partly in the notches of the latter and the casing, thereby to form an interlocked connection between the bolt and the casing.

In testimony that I claim the foregoing as my own I have hereto affixed my signature in the presence of two witnesses.

JOHN ROBERT THOMPSON.
